(57) **CLAIM**

The ornamental design for a nebulizer, as shown and described.

DESCRIPTION

FIG. 1 is a perspective view of a nebulizer showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is the other perspective view showing the nebulizer. The dash-dot-dash broken lines represent the boundaries of the claimed design and form no part thereof. The dash-dot broken lines illustrate portions of the nebulizer which form no part of the claimed design.
